UNITED STATES PATENT OFFICE

111,096

DESIGN FOR A SHOE

Ben Weiner, Brookline, Mass.

Application July 25, 1938, Serial No. 78,691

Term of patent 3½ years

To all whom it may concern:

Be it known that I, Ben Weiner, a citizen of the United States and a resident of Brookline, in the State of Massachusetts, have invented a new, original, and ornamental Design for a Shoe, of which the following is a specification, reference being had to the accompanying drawing, forming part thereof.

Fig. 1 is a plan view of a shoe; and
Fig. 2 is a side perspective view of the same showing my new design.

I claim:
The ornamental design for a shoe, as shown.

BEN WEINER.
